Attorneys

UNITED STATES PATENT OFFICE.

THOMAS B. HENRY, OF NORTHLVILLE, MICHIGAN.

COMBINED TOWEL AND ANTISEPTIC PAD.

1,353,954.

Specification of Letters Patent. Patented Sept. 28, 1920.

Application filed May 23, 1919. Serial No. 299,201.

To all whom it may concern:

Be it known that I, THOMAS B. HENRY, a citizen of the United States of America, residing at Northville, in the county of Wayne and State of Michigan, have invented certain new and useful Improvements in Combined Towels and Antiseptic Pads, of which the following is a specification, reference being had therein to the accompanying drawings.

The invention relates to a combination towel and wash pad particularly designed for surgeons' use, and it is the object of the invention to obtain a compact construction which may be readily carried in a coat pocket and it is always ready for use. To this end the invention consists in the construction as hereinafter set forth.

In the drawings:

Figure 1 is a perspective view of the pad;

Fig. 2 is a cross-section thereof;

Figs. 3 and 4 are plan views, respectively, of the impregnated sheet and the unfolded towel sheet; and

Fig. 5 is a perspective view of the folded towel sheet and removed from the pad.

For surgeons' use, especially in field work, it is frequently necessary to quickly cleanse and sterilize the hands preparatory to a surgical operation. In many instances the water supply may be limited and it is one of the objects of the present invention to provide means which can be carried by the surgeon for convenient use under such limitations. Essentially, my improvement comprises a pad including a series of sheets impregnated with the sterilizing or cleansing agent and also a series of towel or

wiper sheets. The latter are necessarily too large in size to be placed in a pocket without folding, and therefore they are first folded to a convenient size corresponding to that of the impregnated sheet and then bound together in the pad.

As specifically shown, A are the impregnated sheets, and B the towel or wiper sheets, which latter, as shown, are folded along the dotted lines in Fig. 4 to dimensions corresponding with the sheets A. A corresponding number of the sheets A and B are bound together so as to form a pad C that may be conveniently carried in the pocket and which is protected by a suitable cover D. The sheets A may be impregnated with a suitable antiseptic or cleansing agent which is soluble in water.

In use, all that is required in addition to the pad is a limited supply of water, one or more of the sheets A being placed there-in or moistened and rubbed over the hands, after which a towel sheet B may be used for drying. While I have described a device as particularly designed for surgeons' use, it is obvious that it is also adapted for other uses.

What I claim as my invention is:

A pad comprising a series of small sheets of dimensions which will fit within a coat-pocket, said sheets being impregnated with a sterilizing or cleansing agent, a separate series of larger towel or wiper sheets folded to the same dimensions as the smaller sheets and bound together therewith, and a protecting cover for the pad.

In testimony whereof I affix my signature.

THOMAS B. HENRY.
